UNITED STATES PATENT OFFICE.

EDMUND W. WHITED AND CHARLES R. HODGES, OF PITTSBURGH, PENNSYLVANIA.

TOY.

Application filed April 10, 1925. Serial No. 22,182.

The present invention relates broadly to 5 toys and more particularly to toys adapted for material handling, such for example, as excavating or elevating bucket toys or electro-magnetic lifting toys, although the utility of the invention is not limited in this respect, it being apparent that certain of the features are adaptable to commercial installations, and such we consider as constituting part of our invention.

At the present time it is customary both in toys and commercial structures, to provide material handling apparatus comprising grab buckets adapted to be opened at any desired point for permitting discharge of their contents. Ordinarily, however, the trip line for such buckets has required a separate operating drum, and the bucket has been of such construction as not to prevent sifting therethrough of the finer materials being handled.

The present invention has for certain of its objects the provision of improved trip line operating means, as well as the provision of an improved form of grab bucket.

Another object of the present invention is to provide a structure adapted to be readily assembled or dismantled, and comprising an improved form of operating mechanism.

Still another object of the invention is to provide a mechanism of such nature that different forms of material handling units, such as buckets, magnets and the like, may be utilized at will without requiring any substantial change in the operating mechanism.

In the accompanying drawings there are shown for purposes of illustration only, certain preferred embodiments of the present invention, it being understood that the drawings do not define the limits of our invention, as changes in the construction and operation disclosed therein may be made without departing either from the spirit of the invention or the scope of our broader claims.

In the drawings:

Figure 1 is a perspective view of one form of material handling apparatus constructed in accordance with the present invention;

Figure 2 is a view similar to Figure 1, partly broken away, illustrating the grab bucket in open position to permit the discharge therefrom of the contents;

Figure 3 is a detail sectional view through the grab bucket illustrating more clearly the construction thereof;

Figure 4 is a detail sectional view on an enlarged scale on the line IV—IV of Figure 1;

Figure 5 is a front elevational view, partly in section and partly broken away, illustrating in detail a portion of the operating mechanism;

Figure 6 is a side elevational view, partly broken away, of the operating mechanism illustrated in Figure 5;

Figure 7 is a detail sectional view on the line VII—VII of Figure 5;

Figure 8 is a transverse sectional view on the line VIII—VIII of Figure 6 illustrating the construction of one of the operating drums;

Figure 9 is a perspective view similar to Figures 1 and 2, illustrating the grab bucket replaced by an electromagnetic lifting means;

Figure 10 is a bottom plan view illustrating one form of electromagnetic lifting means prior to its completion; and

Figure 11 is a view similar to Figure 10 illustrating the magnetic lifting means in its completed condition.

In carrying out the present invention, there may be provided a material handling apparatus comprising a suitable base 2 having projecting upwardly therefrom a mast 3. This mast may be of any desired construction, but is preferably of substantially rectangular cross section, and is provided at its upper and lower ends with projecting pins 4. These pins are preferably imbedded in the ends of the mast, and have their projecting portions formed with a flat side 5, the remainder of the pins being threaded as clearly indicated. Conveniently, the base 2 is provided with a recess or opening 6 extending therethrough and closed by a foot plate 7 suitably secured to the base. This foot plate is provided with an opening adapted to receive the lower pin 4 to provide a rotatable bearing therefor. After the pin has been inserted through the foot plate, a washer 8 is slipped thereover, and the washer is held in position by a nut 9 threaded onto the pin. In order to prevent the washer from loosening upon rotation of the mast, it is preferably provided with an opening of such shape as to substantially conform to the contour of the pin, as clearly illustrated in Figure 7, whereby rotation of the mast will cause the pin, washer and nut to rotate in unison therewith. By reason of this construction, the nut may be originally

105
110

adjusted as required, to prevent too easy operation of the mast, whereby it may be maintained in any desired adjusted position.

For firmly securing the mast in position, there may be provided a pair of detachable braces 10, having secured to their upper ends plates 11, and to their lower ends similar plates 12. These plates 11 are adapted to be slipped downwardly over the upper pin 4. Thereafter a washer 13, of a construction similar to that of the washer 8, and illustrated in detail in Figure 7, is slipped over the upper pin and a holding nut 14 is threaded downwardly to position thereon.

As illustrated in Figure 4, each of the plates 12 may be formed with an elongated locking slot 15, the slot preferably having one portion thereof enlarged to provide an eye 16. This eye is of such dimensions that it may be bodily moved downwardly over the head 17 of a locking screw or the like projecting upwardly from the base 2. Thereafter, the plates may be slipped laterally to bring the narrow portion of each slot 15 under the head, and thereby firmly secure the plates in position. It will be understood that by reason of this construction the braces may be removed at will, but that when placed in position they provide a firm support for the mast.

Adjacent its lower end the mast is provided with a bracket 18 adapted to receive a pivot pin 19 forming a pivotal mounting for the boom 20. At its outer end the boom is provided with an opening through which extend two pins 21 upon each of which is mounted a pulley 22. Formed in the lower portion of the mast 3, above the bracket 18, is a similar opening 23 having mounted therein similar pulleys 24. Passing over the upper pulley 22 in the boom, and thence downwardly and under the upper pulley 24 in the mast is a hoist line 25. Cooperating with the other pulley of each pair is a trip line 26.

Carried by the mast 3 above the pulleys 24 is an operating mechanism, preferably in the form of an operating unit comprising side plates 27, each secured to one side of the mast. Mounted between these plates is an upper boom operating drum 28 and a lower combined hoisting and trip line drum 29. If desired, the drums may be formed from a single piece of material to provide integral shafts 30, although preferably the drums will be constructed in the form of sleeves adapted to be slipped endwise over separate shafts, and held in position thereon against rotation by means of suitable clamping and set screws 31. As clearly shown in Figure 8, each of the drums is provided with a peripherally extending groove 32, these grooves being of general V-shape in cross section, whereby a line positioned therein tends to become tightly wedged,

thereby being held against movement independently of the drum. The boom drum 28 may be provided with an operating crank 33, while the combined hoist and trip line drum 29 may be provided with a similar operating crank 34. As a matter of expediency, and to permit compactness of construction, these cranks are preferably mounted on opposite sides of the drums, whereby the two cranks may be simultaneously operated without interference.

We have found that conveniently the plates 27 may be utilized not only for the purpose of bearing brackets, but also for the purpose of imposing a braking action on the drums. For this purpose, the plates are preferably provided adjacent each of the drums with a transversely extending screw 35. These screws may have a loose bearing in one of the plates, but preferably have a threaded engagement with the other of the plates. By reason of this construction, it will be apparent that rotation of the screws in the proper direction will be effective for drawing the plates together. In this manner, the plates may be caused to bind more or less against the ends of the drums 28 and 29, thereby holding the drums against too free rotation, and insuring holding of the drums against accidental movement.

In order that the desired braking action may be applied to each of the drums independently of the other, the plates 27 are preferably shaped as clearly shown in Figure 6 to provide a division effective between the drums. Each independent projection thus formed is provided with its own individual adjusting screw 35, whereby accurate adjustment is made possible.

For raising or lowering the boom 20 at will, there is provided a boom cable 36, suitably secured in any desired manner to the upper end of the boom at one end, and thence passing downwardly over a pulley 37 mounted in a suitable opening in the upper end of the mast, to the drum 28. By reason of this construction, it will be apparent that upon rotation of the drum 28 in one direction the boom may be raised, or upon rotation of the drum in the opposite direction it may be lowered to the desired extent. By reason of the braking action imposed on the drum 28 by the plates 27, the drum 28 may be held against too free rotation, thereby preventing accidental lowering of the boom during the operation of the apparatus.

The grab bucket may be conveniently formed of similar sections 38 and 39, preferably formed of sheet material. After the sections have been blanked out, one of the sections is so shaped as to slightly expand one of its edges 40, while the other section is subjected to a suitable forming operation to slightly contract its edge 41. By reason of this construction, one of the sections is

permitted to overlap and extend onto the other section. This overlapping of the section provides a tight joint therebetween preventing any sifting of the material being handled. The sections are in turn pivotally mounted upon a transversely extending pivot pin 42 to the intermediate portion of which is connected one end of the hoist cable 25. Connected to the respective corners of the sections are trip arms 43, these arms all being joined at their inner ends to a common eye 44, to which eye is fastened the trip line 26. With the construction described, it will be apparent that during the normal operation of the parts, the two lines 25 and 26 will be moved a like distance, due to the fact that they are both wound around a common drum. If, however, it is desired to open the bucket at any time, this may be accomplished by shortening the trip line 26 relatively to the hoist line 25, to thereby draw the trip arms 43 upwardly to pull the sections apart. This may be accomplished in accordance with the present invention by means of a trip lever 45 having a pivotal mounting on one of the clamping screws 35, and normally lying in the position clearly shown in Figures 1 and 6. At its lower end the trip lever is formed with an eye 46 through which the trip line 26 passes. By swinging the trip lever from the position illustrated in Figure 1, to the full line position illustrated in Figure 2, the trip line will be drawn out of its normal plane or path of travel, thereby shortening it relatively to the hoist line 25. This will be effective for opening the grab bucket as desired.

The trip lever 45 is preferably constructed of flexible material adapted to be easily shaped as desired. When so constructed, the upper end may easily be bent laterally, as illustrated in dotted lines in Figure 5, when the trip lever is operated, to bring the same into position to be interengaged with the head of one of the screws 35 whereby the bucket will remain open for any required length of time without further attention on the part of the operator.

This construction also possesses another advantage which will be readily apparent from an inspection of Figure 6. By changing the angular relationship of the ends of the trip lever, the relative lengths of the lines 25 and 26 may be correspondingly varied to thereby always insure exactly the required lengths for the proper operation of the parts.

At certain times it may be desirable to replace the grab bucket by another form of lifting means. In Figures 9 to 11, both inclusive, we have illustrated one form of lifting means adapted to be expeditiously substituted for the grab bucket before described. This lifting means may be of electromagnet

type, comprising a casing 48, having three equi-distantly spaced openings 49 formed therein adapted to permit the passage therethrough of lifting links 50. These links at their upper ends may all be joined to a common eye 51, to which are adapted to be connected the trip line 26 and the hoist line 25. A suitable conductor 52 may lead outwardly through another opening 53 in the casing, to a suitable source of current for energizing the magnet. In Figure 10 the casing is illustrated in inverted position as comprising a one-piece casting having a peripherally extending protecting and reinforcing flange and a central core 54. Between the core and the flange is a coil of wire 55 of a size to be easily positioned therein. After the coil of wire has been so positioned, the casing is adapted to be filled with suitable sealing material, such as wax 56, to thereby hold the parts firmly in position and protect the coil against injury. This wax not only protects the coil and holds it in the casing, but also preferably surrounds the lower ends of the lifting links 50 and prevents movement thereof relatively to the casing. This comprises an inexpensive and expedient method of making a lifting means adaptable for use with a toy of the general character herein contemplated.

Where the electromagnet is substituted for the bucket, it will be apparent that either one of the lines 25 or 26 may be used independently of the other, if desired, or both lines may be utilized simultaneously.

If desired, the entire apparatus may be mounted on wheels, casters or the like, to facilitate movement from one place to another.

Certain advantages of the present invention arise from the provision of the material handling apparatus comprising an operating mechanism in the form of a unit having drums mounted in combined bracket and braking means.

Other advantages of the invention arise from the provision of a structure comprising a hoist line and a trip line passing around a single operating drum, and in which the opening or tripping of the part is effected by a separably movable lever. Still other advantages of the invention arise from the provision of the different material handling units, such as a grab bucket, and electromagnetic lifting means, or the like, adapted to be substituted at will.

We claim:

1. Material handling apparatus, comprising a material handling means, a hoist line therefor, a trip line therefor having suitable guiding means, a pivotally mounted trip lever operatively connected to the trip line, the movement of said lever being effective for deflecting the trip line out of the standing position normally assumed, thereby

shortening the effective length of the trip line, substantially as described.

2. Material handling apparatus, comprising an openable bucket, a hoist line therefor,

5 a trip line therefor having suitable guiding means, a common drum for both of said lines, and a pivotally mounted lever operatively connected to the trip line, the movement of said lever being effective for deflecting the trip line out of the standing position normally assumed, thereby shortening the effective length of the trip line and opening the bucket, substantially as described.

10 15 3. A toy material handling apparatus, including a supporting means having side flanges thereon, drums rotatably carried between the flanges, said flanges being held in frictional engagement with the ends of the

20 drums, the frictional engagement between the flanges and the drums being substantially constant, and a line attached to each drum, at least one line having a gravity lowered element attached thereto, the frictional engagement between the flanges and the drums acting to prevent rotation of either drum by the load on the line connected thereto, whereby each drum may be operated independently of the other.

25 30 4. A toy material handling apparatus, including a supporting means having side flanges thereon, drums rotatably carried between the flanges, said flanges being held in frictional engagement with the ends of the

35 drums, the frictional engagement between the flanges and the drums being substan-

tially constant, a line attached to each drum, at least one line having a gravity lowered element attached thereto, the frictional engagement between the flanges and the drums 40 acting to prevent rotation of either drum by the load on the line connected thereto, whereby each drum may be operated independently of the other, and an operating element for each drum.

45 5. A toy material handling apparatus, comprising a mast, a boom pivotally carried by the mast, a control line for said boom, material handling means suspended from said boom, said material handling means

50 having a hoist line and a trip line, a supporting means having side flanges thereon on the mast, drums rotatably carried between the flanges, one of said drums being effective for operating the boom control line, the other drum being effective for simultaneously controlling the hoist line and the trip line of the material handling means, said flanges being held in frictional engagement with the ends of the drum, the frictional force between the flanges and the ends of the drums being substantially constant, the frictional engagement between the flanges and the drums acting to prevent rotation of either drum by the load on the line connected thereto, whereby each drum may be operated independently of the other, and an operating element for each drum.

55 60 65 In testimony whereof we have hereunto set our hands.

EDMUND W. WHITED.
CHARLES R. HODGES.
